UNITED STATES PATENT OFFICE.

JOHN E. BOWEN, OF LAWRENCE, MASSACHUSETTS, ASSIGNOR TO JOHN MANNING VAN HEUSEN, OF BOSTON, MASSACHUSETTS.

MANUFACTURE OF COLLARS AND CUFFS.

1,254,306.

Specification of Letters Patent. Patented Jan. 22, 1918.

Application filed October 20, 1915. Serial No. 58,841.

To all whom it may concern:

Be it known that I, JOHN E. BOWEN, a citizen of the United States, residing at Lawrence, county of Essex, State of Massachusetts, have invented certain new and useful Improvements in the Manufacture of Collars and Cuffs; and I do hereby declare the following to be a full, clear, and exact description of the invention, such as will enable others skilled in the art to which it appertains to make and use the same.

My invention relates to certain new and useful improvements in collars, cuffs, and like articles adapted to be folded along a wearing edge and to then receive a curvilinear set.

In the accompanying drawings,

Figure 1 represents, in end elevation, the forming roll of a loom, in its general relation to the fabric that is being woven;

Fig. 2 represents a plan view, partly broken away, of the parts shown in Fig. 1;

Fig. 3 represents diagrammatically a cross-sectional view of the fabric taken on a plane indicated by the line 3—3 of Fig. 4;

Fig. 4 represents a plan view of a portion of the fabric, the top layer thereof being shown as partially broken away to disclose the interior construction;

Fig. 5 represents a perspective view, partly in section and partly broken away, this view being likewise diagrammatic so as to illustrate more clearly the relative arrangement of the threads of the fabric;

Fig. 6 represents a perspective view of a collar of the folded or turned-down type made from the fabric produced in accordance with my invention;

Fig. 7 represents a portion of the fabric and shows in dotted lines the manner of cutting out a collar blank therefrom;

Fig. 8 represents, in outline, the collar blank cut from the fabric; and

Fig. 9 represents a plan view of the said blank bound, provided with button-holes and ready to be folded and bent into curvilinear form.

Similar letters of reference indicate similar parts throughout the several views.

In the practice of the invention, I am enabled to produce a seamless collar of the folded or turned-down type and one which, by reason of the way in which the fabric is woven will be adapted to receive a curvi-

linear set and at the same time will be smooth and without folds or wrinkles on either its exterior surface or upon its interior or neck-band surface. So also, in the practice of the invention, I am enabled to impart to the fabric a sufficient amount of body to permit it to retain its upright and circular contour, without the use of starch or other stiffening agent. At the same time, the construction of the collar imparts to it sufficient flexibility to accommodate itself, without undue resistance, to the movements of the neck, so that it is devoid of the unyielding rigidity of the customary laundried collar. Furthermore, the fabric is so constructed along the folding or wearing edge that the fold may be made without putting an undue strain upon the fabric along that line and nevertheless without sacrifice of the desired regularity of outline of the wearing edge under the ordinary vicissitudes of wear throughout the varying seasons of the year.

In making up the woven fabric, I construct it, as indicated particularly in Fig. 7, of a strip or a series of strips each made up of two panels *a* *b* with an intermediate fold portion *c* of increased flexibility joining the panels *a* *b* integrally. As illustrated in Fig. 2, it is desirable to weave, in a single piece, upon the same loom, a series of these panel strips, so that the output of a single operation may be correspondingly satisfactory in quantity, and these series of strips may thereupon be sub-divided into individual units, as indicated in Fig. 7. From these units, the blank for the collar may be cut out with a suitable die along the dotted lines shown in Fig. 7. The blank thus cut out is shown in Fig. 8, and this blank may then be bound with suitable tape *d* and may receive the appropriate button-holes as indicated at *e*. The blank may then be folded into the form shown, for instance, in Fig. 6.

By reference to Fig. 6, it will be noted that the inner panel *a'* of the collar, and the outer panel *b'* thereof are both illustrated as presenting smooth un wrinkled surfaces. To accomplish this result, I so weave the individual strips of the fabric that, in the weaving operation a greater stretch will be imposed upon the part from which the panel *b'* is cut than upon the part from which the panel *a'* is cut, so that the alternate panels will be woven longer than the

intermediate panels, and so that the panel *b'* will be longer than the panel *a'*. This is accomplished, as indicated in Fig. 2, by providing the stretcher roll *f* of the loom with 5 raised portions *g* corresponding to the panels *b* and with intervening depressed portions *h* corresponding to the panels *a*. So also, intermediate of the panel *a* and the panel *b* of each strip, I omit certain of the 10 longitudinal or warp threads, so as to lessen the rigidity of the fabric along said intermediate portion. In practice, I find it suitable, in those instances in which the fabric is three-ply, as shown diagrammatically in 15 Fig. 3, to omit say 15 threads, out of 30 in the intermediate layer; it being assumed in this instance, that the number of warp threads to the inch is say three hundred. In Fig. 3, I have very much exaggerated the 20 scale of the weave, and have spaced the threads apart accordingly, so as to more clearly illustrate the intended construction.

Upon reference to Fig. 3, it will also be noted that the spaced warp threads *n* in the 25 intermediate fold portion are shown as not interwoven with the corresponding weft threads *m*. This further contributes to the lessening of the rigidity and to the increasing of the flexibility of the fabric along the 30 intended fold, and permits the fold to be made without putting an excessive strain upon the fabric along the line of bend, which line corresponds to the upper wearing edge of the completed collar. The intermediate 35 weaving of the warp and weft threads of the inner and outer layers of the composite fabric is preferably continuous across the folding edge portion and, by reason of this fact, the weakened intermediate layer is 40 suitably protected, along the fold on both sides thereof. It will, of course, be understood that while, for purposes of clearness and description, I have shown the intermediate edge fold portion as of greatly exaggerated 45 width, it will, in practice, be of a width just sufficient to obtain the necessary fold of the collar, as indicated more fully in Figs. 6 to 9. A greater width than that required for the mere folding of the panels 50 into the form shown in Fig. 6 is to be particularly avoided, for the reason that if the edge fold portion is wider than is necessary for the folding operation, it tends to "break down" while being worn, particularly if it 55 becomes moistened by perspiration. The various plies of the fabric, as will be readily understood, are bound together by the interweaving of individual threads from the one 60 ply to the other during the weaving operation.

As indicated in Fig. 7, the woven strip, or strips, when removed from the loom assume, along the edge fold portion, a curvature, due to the method of weaving hereinbefore described. I find, for instance, that

in weaving the fabric, with the employment of three hundred spun warp yarns to the inch and two hundred weft yarns to the inch, and with the omission of fifteen of the warp yarns along the edge fold portion, I 70 obtain a series of strips wherein the collar blanks, when folded, receive a smooth curvilinear set over the entire surface of both the inner and the outer panels thereof.

It will, of course, be understood that, if 75 desired, the weakening of the fabric along the edge fold portion may be obtained in one of the outer instead of the intermediate layer; or, in the intermediate layer and in one of the outer layers also. This weakening of additional layers may be of particular service in those instances where the yarn chosen is of a character and diameter requiring further weakening to obtain the necessary fold, or where the layers are multiplied beyond three. 80

The invention contemplates the employment of any suitable and desired thread or yarn for the several layers of the fabric, and the selection, for instance, of yarns of different material for the individual layers, as, or instance, where the outer face of the collar may be made of a finer and more expensive yarn than the inner or intermediate layers. It will also be understood that while 95 I have chosen as the best illustration of the invention its adaptation to the manufacture of collars, the invention is also of a scope adapted to serve as the means of production of similar articles such as folded cuffs and 100 the like.

Having thus described my invention, what I claim is:

1. A folding collar or cuff, made up of an inner panel and an outer panel woven in one piece with an intermediate curvilinear weakened edge fold portion; substantially as described. 105

2. A folding collar or cuff, made up of an inner panel and an outer panel woven in one piece with an intermediate curvilinear edge fold portion of increased flexibility, the outer panel being woven under greater tension than the inner panel; substantially as described. 110

3. A folding collar or cuff, made up of an inner panel and an outer panel woven in one piece with an intermediate curvilinear edge fold portion of increased flexibility, the outer panel being woven longer than the inner panel, substantially as described. 115

4. A folding collar or cuff, made up of an inner panel and an outer panel woven in one piece with an intermediate curvilinear weakened edge fold portion, the outer panel being woven longer than the inner panel, substantially as described. 120

5. A folding collar or cuff, made up of an inner panel and an outer panel of multiply fabric woven in one piece with an intermedi- 125

- ate edge fold portion of increased flexibility, the outer panel being woven longer than the inner panel, substantially as described.
6. A folding collar or cuff, made up of an inner panel and an outer panel woven in one piece with an intermediate weakened edge fold portion, the outer panel being woven under greater tension than the inner panel; substantially as described.
10. 7. A folding collar or cuff, made up of an inner panel and an outer panel woven in one piece with an intermediate curvilinear edge fold portion, some of the warp threads of the fabric being omitted in the edge fold portion so as to weaken said portion; substantially as described.
8. A folding collar or cuff, made up of an inner panel and an outer panel woven of multiple fabric in one piece with an intermediate edge fold portion, some of the warp threads of the fabric being omitted in the edge fold portion and some of the weft threads being carried across said edge fold portion without being interwoven therein with the warp threads; substantially as described.
20. 9. A folding collar or cuff, made up of an inner panel and an outer panel woven of multiple fabric in one piece with an intermediate edge fold portion weakened in its interior by the omission of a portion of its warp threads and by the carrying over of a portion of its weft threads without being interwoven with the warp threads, said edge

fold portion being faced exteriorly with interwoven weft and warp threads; substantially as described.

10. In the manufacture of folding collars and cuffs, weaving the fabric from which they are to be cut in panels, one longer than the other, and omitting certain of the longitudinal or warp threads between said panels to give an intermediate weakened curvilinear edge fold portion, substantially as described.

11. In the manufacture of folding collars and cuffs of multiply fabric, weaving the multiply fabric from which they are to be cut in panels, one longer than the other, and modifying the weave between said panels to give an intermediate curvilinear edge fold portion of increased flexibility, substantially as described.

12. In the manufacture of folding collars and cuffs of multiply fabric, weaving the multiply fabric from which they are to be cut in panels, one longer than the other, and omitting certain of the longitudinal or warp threads of one or more of the plies at the intermediate portion between the panels to give a weakened curvilinear edge-fold portion, substantially as described.

In testimony whereof I affix my signature, in presence of two witnesses.

JOHN E. BOWEN.
